(57) **CLAIM**

The ornamental design for a chapel, as shown and described.

DESCRIPTION

- FIG. 1 is a perspective view of the present invention.
 FIG. 2 is a front view of the invention shown in FIG. 1.
 FIG. 3 is a back view of the invention shown in FIG. 1.
 FIG. 4 is a right view of the invention shown in FIG. 1.
 FIG. 5 is a left view of the invention shown in FIG. 1.
 FIG. 6 is a top view of the invention shown in FIG. 1; and,
 FIG. 7 is a bottom view of the invention shown in FIG. 1.
